UNITED STATES PATENT OFFICE.

HILORIUS E. WILDERMUTH, OF COLUMBUS, OHIO.

HALTER-TRIMMING.

SPECIFICATION forming part of Letters Patent No. 540,770, dated June 11, 1895.

Application filed April 16, 1894. Serial No. 507,678. (No model.)

To all whom it may concern:

Be it known that I, HILORIUS E. WILDERMUTH, a citizen of the United States, residing at Columbus, in the county of Franklin and State of Ohio, have invented a certain new and useful Improvement in Halter-Trimmins, of which the following is a specification.

My invention relates to an improvement in halter trimmings of that class which are designed to couple together the various parts of the halter and has particular relation to the improvement of the device for which Letters Patent No. 252,500 were issued on the 17th day of January, 1882.

15 The object of the present invention is to provide a more reliable and effective trimming or coupling which consists in improvements in the details of construction which will be more fully pointed out hereinafter.

20 I accomplish the object of my invention in the manner illustrated in the accompanying drawings, in which—

Figure 1 is a view in perspective of a portion of the nose-strap and portions of the 25 cheek-strap, which are connected therewith by means of my improved trimming. Fig. 2 is a central longitudinal section of the trimming or coupling device. Fig. 3 is a sectional view on line $\alpha\alpha$ of Fig. 1, and Fig. 4 is a plan view of said device.

Similar letters refer to similar parts throughout the several views.

In the construction of my improved trimming or coupling, I employ a metallic oblong frame a having parallel sides and ends, said ends being, as shown, inclined to a slight degree from a right angled position with the sides. The nose b or one end of the coupling is formed by having the width of the frame 35 slightly decreased and the end inclined downward, the latter feature being indicated in Fig. 2 of the drawings. As indicated at c the opposite end portion of the coupling has, unlike the device shown and described in the 40 above mentioned patent, its upper side substantially of even height with the parallel side portions of the coupling.

Formed with the under side of the nose portion b is a transverse keeper bar d which, 50 as shown in the drawings, is depressed below the body of the coupling. From the center of the length of this bar d extends longitudi-

nally in the same plane therewith to a point beneath the end portion c of the coupling a bar or arm e , the latter having formed therein 55 at a point near said end portion c a laterally enlarged portion f . At the center of the width of the cross bar d and center of the length of the arm e , I provide respectively upwardly projecting pins or studs g and h .

As indicated in section in Fig. 3 of the drawings, the longer side arms a' of the coupling body are inclined outward and downward. As indicated at i the inner side or edge of one of the side frame pieces a' is cut away for the 65 purpose hereinafter set forth.

The manner of utilizing my invention for the connection of one of the ends of the cheek strap k with that portion k' of the nose strap which is looped as indicated to hold in the 70 usual manner a buckle k^2 , is substantially as follows: The end of the strap k is inserted within the frame a , said strap end passing beneath the end of the nose b and over the bars d and e . The inserted portion of the 75 strap is provided with pin holes, through which pass and with which engage the projecting studs g and h of said bar portions. This having been accomplished the doubled portion k' of the nose strap, is inserted transversely through the coupling or trimming frame by passing the same beneath one of the side arms a' , thence over the longitudinal bar e and out under the remaining side arm a' . This strap portion k' is also provided with a 80 pin hole which is adapted to receive the upwardly projecting stud h of the bar e .

It will be observed that owing to the incline of the frame side pieces a' , the strap portions which pass beneath the same will be 85 depressed as indicated in Fig. 3 of the drawings, this depression operating to prevent the strap slipping off the retaining stud.

It will be observed that the substantially square shoulder formed by the horizontal end 90 portion c of the frame, will provide a side bearing for the strap k' and operate to prevent any lateral movement of said strap in that direction. It will also be observed that the depression of the nose portion b will in a 95 like manner operate to produce a slight inward or downward bend of the strap k , which will serve to hold the latter in engagement with the studs.

In forming or coupling the trimming frames or bodies, I provide two patterns, one having the ends thereof inclined in one direction and the other having said ends inclined in the opposite direction, thus producing what may be termed rights and lefts which are adapted to be used on opposite sides of the halter and which impart to the cheek straps the desired angle with the nose strap.

10. By means of the enlargement *f* at the inner end of the bar *e*, an additional bearing surface for the inner end of the strap *k* is produced which will operate to prevent any displacement of the latter. The depression *i* which is formed on the inner edge of one of the bars *a'* provides more room for the insertion of doubled strap portions on that side where the thickness is greatest.

Experience has demonstrated that the variations in the construction herein shown and described over that of the device described and claimed in said former patent, are necessary for a more complete and perfect operation of the trimming or coupling and that by the use of these improvements no necessity exists for the employment of any other fastenings of the halter portions such as rivets, &c.

25. Although I have described the connection

of the nose strap and one end of the cheek strap, it is evident that other parts of the 30 halter may be connected and the trimming employed in substantially the same manner.

Having now fully described my invention, what I claim, and desire to secure by Letters Patent, is—

35. A harness trimming consisting of a frame having parallel side and end bars, the side bars *a' a'* being inclined downwardly from their inner to their outer edges and being also bent downwardly at one extremity to bring 40 one end bar *b* below the plane of their inner edges, the upper edge of the other end bar *c* being in substantially the same plane as the inner edges of the side bars, a cross bar *d* connected to the side bars and depressed below 45 the body of the frame, an arm *e* connecting the cross bar and the end bar *c*, said arm being in the same horizontal plane as the cross bar, and studs projecting from the cross bar and the arm, substantially as and for the purpose specified.

HILORIUS E. WILDERMUTHII.

In presence of—

C. C. SHEPHERD,

F. A. SIEGEL.
